UNITED STATES PATENT OFFICE.

JOSEPH F. HANRAHAN, OF BUFFALO, NEW YORK.

DRYING-KILN.

No. 820,865.

Specification of Letters Patent.

Patented May 15, 1906.

Application filed March 31, 1905. Serial No. 253,098.

To all whom it may concern:

Be it known that I, JOSEPH F. HANRAHAN, a subject of the King of Great Britain, residing at Buffalo, in the county of Erie and State of New York, have invented certain new and useful Improvements in Drying-Kilns, of which the following is a specification.

My present invention pertains to improvements in drying-kilns, the construction and advantages of which will be hereinafter set forth, reference being had to the annexed drawings, wherein—

Figure 1 is a transverse sectional view of a battery of kilns; Fig. 2, a longitudinal sectional view taken on the line 2 2 of Fig. 1, and Fig. 3 a transverse sectional view of a modified form of kiln.

The object of my invention is to provide a kiln in which all portions of the material under treatment shall be equally subjected to the action of the air which is drawn therethrough, the arrangement being such that the air is evenly distributed therein.

With the construction hereinafter set forth in detail the air is brought in the full length of the chamber or kiln and completely distributed from one wall thereof to the opposite wall before it comes under the influence of the heat radiating from the heating-pipes. An opening or outlet for the moisture-laden air is also provided, which outlet extends the full length of the chamber. Suitable regulators are employed to control the flow of the air into and out of the kiln, thereby controlling the effect of the air upon the lumber or other material and preventing in the first instance a too rapid drying thereof, which will have a tendency to case-harden the same and prevent the moisture from passing out from the center or core of the wood.

Referring first to Figs. 1 and 2, A, B, and C denote a series or battery of kilns each provided with cross-bars or supports D, upon which are mounted tracks E for the reception of trucks or carriers for the lumber or other material to be dried. Heating-pipes F are mounted upon or supported by the cross-bars D, which bars, as will be seen upon reference to the drawings, are located a considerable distance above the floor of the kiln. An air inlet or duct G, provided with a suitable regulator H, opens into the lower portion of the kiln at a distance below the cross-bars D. This duct or inlet G extends the entire length

of the kiln, so that the fresh air introduced therethrough enters the kiln through its whole length. If desired, a deflector or baffle-plate I may be employed at the lower end 60 of the duct or chamber G to divert the air in the direction indicated by the arrows in the drawings. The air entering by the duct being spread over the floor of the kiln from side to side will gradually pass upwardly and 65 come under the influence of the heat radiated from the pipes. As the air becomes heated it will naturally ascend and be displaced by that drawn in through the duct. The heated air passes up through the charge and out by 70 stack or outlet J, which is provided with a regulator K. Said stack or outlet J likewise extends throughout the entire length of the kiln, so that the heated and moisture-laden air has a free exit from the kiln. The rapidity with which the air passes from outlet J 75 and into the duct G will of course be determined by the degree of opening of the regulators or valves H and K. As before noted, when the lumber is first placed in the kiln 80 the degree of heat desired is somewhat lower than that employed during the later stages of the drying operation, and the valves are therefore adjusted accordingly.

In Fig. 3 a slight modification of the invention is illustrated. Instead of employing the duct G, which is necessary in case a series or battery of kilns is used, at least for the innermost ones, I form an opening L at the lower portion of the kiln and provide a regulating- 85 valve M for said opening. The dry cool air passes in through this opening beneath the heating-pipes and spreads from side to side of the kiln before being affected by or coming under the influence of the heating-pipes. As 90 in the former construction, the rapidity with which the air passes through the kilns may be regulated and determined by proper manipulation of the valve M and outlet-valve K', formed in the outlet passage or flue J'. The 95 exact location of the outlet or chimney is immaterial. While I have shown it as placed upon the same side as the inlet-flue, it may of course be placed upon the opposite side. The form of valve or damper for regulating 100 the inflow and exit of the air is also immaterial. Any form which will accomplish the purpose in view falls within the scope of my invention.

If desired, a curtain P may be employed, 110 as shown in Fig. 2, to divide the kiln into an initial sweating-chamber and a final drying-

chamber, the curtain being operated in the usual manner.

Having thus described my invention, what I claim is—

- 5 1. In a drying-kiln, the combination of a chamber provided with an air-inlet extending substantially the entire length thereof near the bottom of the chamber and opening directly into the same, said chamber being likewise provided with an opening in the upper portion thereof extending substantially the length of the chamber; air-heating means located in the chamber at a point substantially above the bottom thereof; means for regulating the amount of air which may pass into said chamber through the lower opening; and means for regulating the outflow of the air through said upper opening.
- 10 2. In a drying-kiln, the combination of a chamber having an opening formed at the lower portion thereof, said opening extending substantially the entire length of the chamber and having a free and unobstructed inlet directly into the same, said chamber being likewise provided with an opening in the upper portion thereof extending substantially the length of the chamber; means for regulating the size of said lower opening; a series of cross-bars or supports mounted in the

chamber; a series of heating-pipes supported 30 by said cross-bars, the bars and pipes being elevated sufficiently to permit the air which enters the opening in the lower portion of the kiln to pass to the opposite side thereof before coming entirely under the influence of 35 the heat radiated from the pipes; and means for regulating the escape of the heated, moisture-laden air through said upper opening.

3. In a drying-kiln, the combination of a chamber provided with an air-inlet extending substantially the entire length thereof 40 near the bottom of the chamber and opening directly into the same, said chamber being likewise provided with an opening in the upper portion thereof extending substantially 45 the length of the chamber; air-heating means located in the chamber at a point substantially above the bottom thereof; and means for regulating the amount of air which may pass into and through said chamber.

In testimony whereof I have signed my name to this specification in the presence of two subscribing witnesses.

JOSEPH F. HANRAHAN.
